FUEL SYSTEM FOR ENGINES

Nathan C. Price, Berkeley, Calif., assignor to
 Universal Engine and Propeller Co., Alameda,
 Calif., a corporation of California

Application May 11, 1937, Serial No. 142,001

9 Claims. (Cl. 123—119)

The present invention relates to a fuel induction system especially adapted for aircraft engines.

The principal object of the invention is to provide a fuel induction system of the positive pressure or super-charger type in which the liquid fuel is properly proportioned to the air at all times and under all conditions of speed, load, and atmospheric pressure. A second object is to provide a system in which the air and liquid fuel are kept separate until just before entering the engine cylinder, and in which the liquid fuel distribution lines leading to the various cylinders are housed within the air induction system, thereby improving vaporization of the fuel by subjecting it to the increased temperature of the air delivered by the super-charger blower, and eliminating any danger from fire in the event of leakage from a fuel line. Another object is to provide a system in which the high tension ignition distributor and the conductors leading to the spark plugs of the cylinders are housed within the air induction system, thereby subjecting them to super-atmospheric pressure and preventing corona discharge losses from said distributor and conductors under the conditions of reduced atmospheric pressure encountered at high altitudes.

These and other objects and advantages of the invention will become apparent from the following specification, which should be read with the understanding that changes, within the scope of the claims hereto appended, may be made in the form, construction, and arrangement of the several parts herein shown and described, without departing from the spirit of the invention as defined in said claims.

A preferred form of the invention is herein described and illustrated as embodied in an aircraft engine of the radial cylinder type. It will be apparent, however, that the invention can be applied to engines of other types without material change. Only such parts of the engine as are pertinent to the invention are shown and described herein.

In the drawings,

Fig. 1 is a partial rear end elevation of an engine provided with my fuel induction system.

Fig. 2 is a part sectional front end elevation, enlarged, of the induction manifold.

Fig. 3 is a longitudinal section of the rear end portion of the engine taken on the line 3—3 of Fig. 1, and enlarged, showing the air blower and fuel distributor.

Fig. 4 is a plan view, enlarged, of the fuel compensator.

Fig. 5 is a vertical section of the same, taken on the line 5—5 of Fig. 4.

Fig. 6 is a partial vertical section of the same, 5 taken on the line 6—6 of Fig. 4.

Fig. 7 is a part sectional side elevation of the rear end portion of the engine, showing the position of the fuel compensator with respect to the air intake and blower, the sectional portions 10 being taken in a vertical plane indicated by the line 7—7 of Fig. 1.

Fig. 8 is a diagram showing the functional arrangement of the several parts.

Throughout the following specification, the word fuel will be used as meaning liquid fuel capable of being vaporized or atomized and burned in the engine cylinder when mixed in proper proportions with air and suitably compressed. The fuel may be gasoline of high volatility, for which the particular engine herein illustrated has been designed, or it may be some other fuel of lower volatility. The invention contemplates a blower or other means for supplying air to the cylinders under super-atmospheric pressure, means for supplying fuel under constant pressure, a fuel compensator for regulating the amount of fuel supplied in proper proportion to the amount of air under all conditions of operation, and a conduit system for separately conducting the air and the fuel to the intake ports of the cylinders, said fuel being sprayed into the air stream at points close to said intake ports.

Referring more particularly to the drawings, the reference numeral 11 designates the main shaft of the engine, 12 is the crankcase, and 13, Figs. 1 and 2, are the rear cylinders of two adjacent banks or rows. The number of cylinders in each bank is immaterial, as is the number of banks. All the cylinders of each two adjacent banks are served by a common intervening manifold 14 having suitably spaced branches 15 connected with the cylinder inlet ports 16. The exhaust manifolds and the inlet and exhaust valves of the cylinders are immaterial to the present invention, and are therefore illustrated conventionally in the diagram, Fig. 8, in which only one cylinder is shown for the sake of simplicity.

At the rear end of the engine the manifold 14 turns inwardly, i. e. toward the shaft 11, and connects with a branch 17 leading outwardly from the discharge duct 18 of a blower 19, Fig. 3, which surrounds and is driven by the shaft 11, and has an inlet chamber 20. The blower draws 55

air in through an inlet pipe 21, Fig. 7, having a butterfly valve 22 which is the throttle valve of the engine. It will be seen that the parts hereinbefore described constitutes an air induction system, the air being drawn in through the throttle controlled intake 21 by the blower 19, and forced out to the various cylinders, at super-atmospheric pressure, through the manifold 14. There may be as many manifolds as is necessary 10 to supply all the cylinders, each such manifold being connected as described with the common discharge duct 18 of the blower.

Fuel is supplied at constant pressure from any suitable source, not shown, and its flow is regulated in a compensator 23 mounted at the rear of the engine as indicated in Figs. 1 and 7. This compensator, which is shown in detail in Figs. 4, 5 and 6, has a fuel regulating valve which is controlled both by the flow or velocity pressure of the air in the intake 21 and by the flow or velocity pressure of fuel itself. The fuel enters the unit through a pipe 24, and passes through a venturi throat 25, thence through the regulating valve and out through a pipe 26. The 20 regulating valve is a plug 27, slidable in a cylinder 28. The upper end of said plug moves toward and away from a seat 29, thereby varying the flow of fluid through the outlet 26. The valve plug 27 has a small central port 30, which 30 is closed at its lower end by a needle formed upon the upper end of a stem 31. A piston 32 on said stem operates in a cylinder 33. The lower end of said cylinder, below the piston 32, is open to the pressure of the fuel in the supply line, through a passage 34. The upper end of the cylinder 33, above said piston 32, communicates with the throat of the venturi through passages 35. The piston 32 is therefore affected by a pressure differential which is a function of the fuel flow, an increased flow increasing the pressure differential and tending to raise the piston, and a decreased flow tending to lower said piston. The arrangement of the ported valve plug 27 is such that it tends to keep itself seated lightly 40 on the stem 31, and therefore follows the movements of said stem. A needle valve 36, adjustable from the exterior, is provided to regulate the effective area of the venturi throat.

The stem 31 extends downwardly through a 50 guide bushing 37, and carries a second and larger piston 38, operating in a cylinder 39. The lower end of said cylinder 39, below the piston 38, is connected by a passage 40 and pipe 41, Fig. 7, with the air intake 21. The upper end of said cylinder, above the piston 38, is open to the atmosphere through a passage 42 and a screen 43, Fig. 6. The lower side of said piston 38 is therefore exposed to the sub-atmospheric pressure in the air intake 21, and its upper side is 55 exposed to atmospheric pressure. Hence the piston 38 is acted on by the pressure differential existing between the air intake and the atmosphere, which is a function of the flow of air to the engine. A spring 44 tends to resist the effect of said air pressure differential.

It will be seen that the air piston 38 and the fuel piston 32 work in opposition. As the throttle 22 is opened and more air flows through the intake 21, its pressure falls and the air piston 38 60 and the stem 31 move down, thereby opening the fuel valve 27 and allowing more fuel to flow. Such increased flow of fuel, however, increases the pressure differential affecting the fuel piston 32, which resists the downward movement of the stem 31. By properly proportioning the various

parts, the device can be made to regulate the fuel in proper ratio to the air supply under all conditions of the latter.

The fuel compensator provides a further automatic regulating function, to compensate for variations in atmospheric pressure due to changes in altitude. This function is accomplished by an aneroid element 45, Fig. 6, mounted in a chamber 46 and exposed to the atmosphere through an aperture 47. The upper end of said aneroid element is fixed at 48, and its lower end carries a needle valve 49 which obstructs, to a greater or less extent, the air inlet 42 leading to the air cylinder 39. The passage below the valve 49, shown at 50 in Fig. 6, is for construction purposes only, and has no operating function. There is a constant flow of air through the passage 42, due to the pressure differential on the piston 38 and the leakage around it. As the atmospheric pressure decreases, due to altitude, the element 45 expands, causing its valve 49 to move down and further obstruct the passage 42. This reduces the flow of air through the cylinder 39, thereby reducing the effect of the sub-atmospheric pressure in the air intake 21, and reducing 20 the fuel to air ratio. Thus the proper proportions of fuel and air are automatically maintained under all conditions of throttle opening and atmospheric pressure.

From the compensator 23, the fuel passes 30 through the pipe 26 to one or more timing and distributing valves 26a (Fig. 8), the number thereof depending upon the number and arrangement of the engine cylinders. The drawings herein illustrate one such timing and distributing valve, designed to distribute fuel to all cylinders of the two banks served by the air induction manifold 14.

At the rear of the engine, the crankcase is provided with a suitable extension 51, Figs. 1 and 3, in which the fuel distributor is housed immediately behind the blower and approximately in line with the end of the manifold 14. The distributor comprises a fixed member bolted to the housing and having an annular upper head 52, Fig. 3, and a central shank 53 extending downwardly therefrom. Within the head 52 is a hardened and ground annular sleeve 54, and within said sleeve is a rotor 55 fixed upon a vertical shaft 56. A plate 57 is bolted to and closes the top of the head 52, said plate having an upward extension in which is mounted a ball bearing 58 for the shaft 56. The lower end of said shaft carries a bevel gear 59, and a second ball bearing 60 is mounted between an upstanding flange on said gear and the stationary shank 53. The two bearings 58 and 60 centralize the rotor 55 accurately within the stationary sleeve 54.

Packing 61 is provided around the shaft 56, 60 preferably at three points, viz: the upper and lower ends of the shank 53, and in the shank of the cover plate 57. Each packing is compressed by a spring 62 held in place by a suitable retainer 63.

The head 52 and its sleeve 54 are provided with a radially disposed inlet opening 64 with which the fuel inlet pipe 26 communicates, and with a plurality of properly spaced radial discharge openings, one of which is shown at 65, said discharge openings being positioned in a horizontal plane above the inlet opening 64. The inlet opening admits the fuel to a space below the rotor 55, and the peripheral flange of said rotor is provided with a port 66 which registers succe- 75

sively with the several discharge ports 65 to permit discharge of said fuel. The rotor is driven by suitable gearing 67 connecting the gear 59 with the engine shaft 11.

5 Each discharge port 65 of the distributor head 52 communicates, through a suitable connection 68, with a fuel line 69 leading to one of the engine cylinders. All such fuel lines 69 are led through an open passage 70 which connects the interior 10 of the distributor housing 51 with the blower discharge branch 17 and the air induction manifold 14, and thence are carried inside said manifold, as indicated in Figs. 1 and 2, to the respective cylinders connected therewith. In Fig. 3, 15 only four fuel lines 69 are shown, to avoid confusion, but it is to be understood that there will be as many such fuel lines as there are cylinders supplied by that particular distributor. In Figs. 1 and 2, eight fuel lines are shown within the air 20 manifold 14. They may be mounted in the manifold in any suitable manner.

At each branch 15 of the manifold 14, one fuel line 69 is led off into said branch, and terminates in a socket 71 formed in the wall of said branch 25 adjacent the cylinder inlet port 16. An injection nozzle 72, of any suitable type, is mounted in the socket 71, and serves to spray the fuel into the air stream as said air passes into the cylinder inlet port.

30 It will be seen from the foregoing and by reference to Fig. 8 that the fuel distributor and the fuel distribution lines leading to the various cylinders are housed within the air induction system. The interior of the distributor housing 51 is open 35 to the air manifold through the passage 70. Any fuel which may leak from a broken or defective fuel line will be drawn into the engine through the air manifold. Any fuel that may leak from the distributor can be drained off from the bottom 40 of the housing 51 in any suitable manner, as for example by a small aperture 73, Fig. 3, leading into the air intake chamber 20, from which it will be drawn into the engine. The only exposed fuel pipes are the inlet pipe 24 leading from the 45 pump or other source of supply of the compensator 23, and the short pipe 26 leading from said compensator to the distributor. The danger from fire in the event of a broken or leaky fuel line is therefore reduced to a minimum. Moreover, 50 housing the fuel distribution lines within the air manifold subjects the fuel to the temperature of the air within said manifold, which is always above atmospheric temperature because of its super-atmospheric pressure, and thereby 55 insures vaporization of said fuel. In order to insure equal distribution of fuel to all cylinders, the shorter fuel distribution lines are made slightly smaller in diameter than the longer lines. By properly proportioning the diameter of said 60 lines to their length, the friction in all can be made equal.

An ignition distributor 74, Fig. 3, is mounted in the upper portion of the housing 51 above the fuel distributor, and is driven by the shaft 56. 65 The construction of said ignition distributor forms no part of the present invention, and has been omitted from the drawings. Its position, however, within and enclosed by the housing 51, and the disposition of the high-tension conductors 75 leading from said ignition distributor to the spark plugs of the several cylinders, are material to the invention. The high tension conductors 75 are led from the distributor housing 51 through an enclosed passage 76 to an annular channel 77 formed in the crank case at the rear

end of the engine. The channel 77 is provided with a pressure-tight cover plate 78. From said channel the conductors 75 are led out to the various spark plugs shown only at 79a in Fig. 8, each conductor being encased in the usual flexible metallic conduit 79 which serves both as a protective covering for the insulation of the conductor, and as an electro-magnetic shield to prevent radio interference. At the point where each conductor leaves the enclosed channel 77, one 10 being shown in Fig. 3, the shield conduit 79 is connected with the cover plate 78 by a bushing 80 which is pressure tight, as well as providing an electrical ground for said shield.

As a result of this construction, the ignition distributor 74 and the high-tension conductors 75 are subjected to the super-atmospheric pressure of the air induction system. Suitable apertures 81 are provided between the base of the ignition distributor 74 and the housing flange 82 on which it rests, so that the pressure within the fuel distributor housing passes into the ignition distributor housing, and thence through the passage 76 into the channel 77. The ignition distributor housing is provided with a tight cover 83. The pressure tight bushings 80 permit the super-atmospheric pressure to the channel 77 to pass into the flexible shield conduits 79 of the conductors 75, so that said conductors are maintained under super-atmospheric pressure 30 throughout their length. Corona losses, which would otherwise occur through the insulation and from the various conducting elements of the ignition distributor at the reduced air pressure 35 encountered at high altitudes, are thereby prevented. In as much as the fuel is not mixed with the air until just before it enters the cylinder, there is no danger of ignition of said fuel by accidental electrical discharge from those portions of the electrical system that are housed within the air induction system.

I claim:

1. In an internal combustion engine having a cylinder, means for supplying air to said cylinder under super-atmospheric pressure, means for supplying fuel to said cylinder, an electric ignition system including a distributor for the ignition current, and an air tight housing inclosing said distributor, the interior of said housing being exposed to the pressure of said air supply.

2. In an internal combustion engine having a cylinder, an air induction system therefor operating at super-atmospheric pressure, means for supplying fuel to said cylinder, and an electric ignition system having a portion thereof housed within said air induction system.

3. In an internal combustion engine having a cylinder, an air induction system therefor operating at super-atmospheric pressure, a fuel supply system, and an electric ignition system, portions of said fuel and ignition systems being inclosed within said air induction system and exposed to the super-atmospheric pressure thereof.

4. In an internal combustion engine having a cylinder, an air induction system therefor operating at super-atmospheric pressure, a fuel supply system including a timing and distributing valve, an electric ignition system including a distributor for the ignition current, a housing 70 enclosing said fuel distributing valve and said ignition distributor, and means for conducting the super-atmospheric pressure of said air induction system to the interior of said housing.

5. In an internal combustion engine having a

plurality of cylinders, means for supplying air under super-atmospheric pressure, a manifold for conducting said air to said cylinders, means for supplying fuel, means for automatically maintaining a predetermined fuel to air ratio, a fuel distributing valve, and conduits for conducting the fuel from said distributing valve to the respective cylinders, said conduits being positioned wholly within said manifold and discharging 10 said fuel into the supplied air adjacent the cylinder intakes.

6. In an internal combustion engine having a cylinder, an air induction conduit for supplying air to the intake of said cylinder, means in said 15 conduit driven by the engine for raising the pressure of the air flowing therethrough above atmospheric pressure, means for supplying fuel, a movable valve operated by the engine for timing the supply of fuel to the cylinder, an air-tight housing 20 inclosing said fuel timing valve, a branch conduit connecting said air induction conduit with said housing, and a fuel distribution pipe leading from said timing valve through said branch conduit and said air induction conduit, 25 said pipe terminating at a fuel discharge orifice positioned within said air induction conduit adjacent to the cylinder intake.

7. In an internal combustion engine having a cylinder, an air induction conduit for supplying air to the intake of said cylinder, means in said 30 conduit driven by the engine for raising the pressure of the air flowing therethrough above atmospheric pressure, means for supplying fuel, a movable valve operated by the engine for timing 35 the supply of fuel to the cylinder, an air-tight housing inclosing said fuel timing valve, a branch conduit connecting said air induction conduit with said housing, a fuel distribution pipe leading from said timing valve through said branch conduit and said air induction conduit, said pipe 40 terminating at a fuel discharge orifice positioned within said air induction conduit adjacent to the

cylinder intake, and a drain conduit connecting said housing with said air induction conduit.

8. In an internal combustion engine having a cylinder, an air induction conduit for supplying air to the intake of said cylinder, means in said conduit driven by the engine for raising the pressure of the air flowing therethrough above atmospheric pressure, means for supplying fuel, a shaft rotated by the engine, a fuel timing valve and an electric ignition timer positioned in adjacent relation and driven by said shaft, an air-tight housing inclosing said fuel timing valve and said ignition timer, a branch conduit connecting said air induction conduit with said housing to raise the pressure therein, a fuel distribution pipe leading from said timing valve through said branch conduit and said air induction conduit to a discharge orifice adjacent the cylinder intake, an electric conductor leading from said ignition timer to the cylinder, and an air-tight 15 conduit surrounding said conductor, the last mentioned conduit opening into said housing and receiving pressure therefrom.

9. In an internal combustion engine having a cylinder, an air induction system having a pressure tight conduit for supplying air under super-atmospheric pressure to the intake of said cylinder, means for supplying fuel under super-atmospheric pressure, fuel metering means for maintaining a predetermined fuel to air ratio, said 25 metering means being outside said air induction system and being controlled by the pressure differentials between the air in said induction system, the fuel, and the atmosphere, a movable valve operated by the engine for receiving the 30 fuel from said metering means and timing the supply thereof to the cylinder, said valve being positioned within a portion of said air induction conduit, and a fuel pipe leading from said valve, through said conduit, said pipe terminating at a 35 discharge orifice within said conduit adjacent to the cylinder intake.

NATHAN C. PRICE.
